CLAIM

The ornamental design for a combined tape rule and
key ring, as shown and described.

DESCRIPTION

FIG. 1 is a top plan view of a combined tape rule and
key ring showing my new design;

FIG. 2 is a right side elevational view, the left side being
a mirror image thereof;

FIG. 3 is a front elevational view thereof;

FIG. 4 is a rear elevational view thereof;

FIG. 5 is a bottom plan view.

FIG. 1

FIG. 3
